UNITED STATES PATENT OFFICE.

EDWARD F. WOODWARD, OF BROOKLYN, NEW YORK.

LADY'S SKIRT.

Specification of Letters Patent No. 17,602, dated June 16, 1857.

To all whom it may concern:

Be it known that I, EDWARD F. WOODWARD, of Brooklyn, in the county of Kings and State of New York, have invented certain new and useful Improvements in Stiffening Ladies' Skirts or Bustles and other Articles of Dress; and I do hereby declare the following to be a description thereof in which my invention is fully ascertained and set forth, reference being had to the following drawing, in which—

Figure 1, is a view of the skirt with the new improvement. Fig. 2, is a cord detached. Fig. 3, modification of ditto.

Heretofore the mode adopted in the present fashion of skirts is to form hoops of the very expensive material whale bone or of the interior substance of the ratan (*Calamus rotang*) from which the outer silicious substance has been removed. These appliances as well as coarser ones are heavy, cumbersome, and quite too rigid, they do not permit an easy graceful flow of the drapery of a lady's dress so essential to the beauty of costume and when acted upon by the wind they show conspicuously and inelegantly. I effectually remedy these defects by my improvements and form a light buoyant fabric having all the necessary stiffness for the purpose and at the same time an elasticity and pliability not before found in the articles now in the market.

My invention is constructed as follows: I shave the center portion of the *Calamus rotang*, or common ratan, or such other analogous reed or substance as shall be found the equivalent thereof after the outer silicious portions of it have been removed in strips, I cut it into shavings, or I employ the waste shavings of this substance when produced in any of the manufactures of

ratan. These shavings or fibers however produced I quilt between proper materials for forming the pads of the skirt in the required form. If I require, as in most cases 45 I do, to have the additional aid of a cord or stiffener to the spiral about to be described which I put around the bottom or elsewhere I take a cord of hemp or other material and wind around it a spiral strip of the outer 50 silicious portion of the ratan before named which has been previously steamed to soften it. This when again dried becomes stiff and elastic and forms a substitute every way superior to the articles heretofore in use, 55 which yield to external pressure without the rigidity of a hoop, while it springs into place with the same force when relieved. I sometimes propose to use the spirals of ratan without the interior cord. This is sewed, 60 woven, or quilted into the skirt, and produces the effect with great lightness. I propose also to saturate this material with gum shellac, or seedlac, or some other analogous gum that adds increased stiffness and durability 65 and prevent their becoming limber by wear, and to substitute nutal in some cases. The manufacture of this cord can be effected by any convenient machinery.

Having thus fully described my improved 70 articles of ladies' dress what I claim therein as new and for which I desire to secure Letters Patent is—

The employment of the spiral stiffener or cord for stiffening ladies' skirts, &c., together 75 with the saturation thereof in manner set forth and for the purposes specified.

EDWARD F. WOODWARD.
